[57] CLAIM

The ornamental design for a telephone shelter, as shown
and described.

DESCRIPTION

FIG. 1 is a perspective view of a telephone shelter
showing my new design;

FIG. 2 is a rear elevational view thereof;

FIG. 3 is a side elevational view, the opposite side being
a mirror image thereof;

FIG. 4 is a front elevational view thereof; and

FIG. 5 is a top plan view thereof.
